DEVICE FOR SHARPENING MILLED CURVED
TOOTH FILES

William E. Edwards, Gonzales, Tex.

Application August 5, 1953, Serial No. 372,527

4 Claims. (Cl. 51—96)

This invention relates to abrading machines, and more specifically, to devices for sharpening manually manipulated tools.

One of the primary objects of this invention is to provide a device for sharpening milled curved tooth files.

A further object of this invention is to provide a sharpener of the type described which is non-complex in construction, inexpensive to manufacture and to maintain, and which does not require the services of a skilled mechanic to operate.

A still further object of this invention is to provide a sharpener which will accommodate files of varying widths and thicknesses and which makes the accommodation automatically.

Another object of this invention is to provide a step-by-step positioning means for the file whereby each tooth of the file is brought, successively, into proper position for the sharpening operation.

Other and further objects and advantages of this invention will become more apparent from a consideration of the following specification when read in the light of the accompanying drawings, in which:

Fig. 1 is a top plan view of a file sharpener constructed in accordance with the teachings of this invention;

Fig. 2 is a longitudinal cross-sectional view taken on the vertical plane of line 2—2 of Fig. 1, and looking in the direction of the arrows;

Fig. 3 is an end elevation of the sharpener shown in Fig. 1;

Fig. 4 is a cross-sectional view taken on the vertical plane of line 4—4 of Fig. 2, and looking in the direction of the arrows;

Fig. 5 is a partial top plan view of the file holder;

Fig. 6 is a partial enlarged side elevation illustrating the engagement of the sharpening means with a file groove; and,

Fig. 7 is a top plan view of the file holder.

Referring now more specifically to the drawings, reference numeral 1 designates, in general, a file sharpener constructed in accordance with the teachings of this invention. As shown in Figs. 1, 2, 3 and 4, the sharpener 1 comprises a substantially hollow support member 2 having an inverted, substantially U-shaped transverse cross-section, and including a horizontal top wall 3 having integrally formed depending spaced side walls 4 and 5 which terminate at their lower ends in integrally formed, opposed, and outwardly turned flanges 6 and 7, respectively. The side walls 4, 5 and their respective flanges 6, 7 are inclined at an angle with respect to each other and converge toward the open front end 8 of the support member 2. Referring to Fig. 1 of the drawings, it is seen the rear end 9 of the top wall 3 is arcuate in configuration and that the support member 2 is symmetrical in and about its longitudinal axis.

The flanges 6, 7 are transversely apertured to receive therethrough a plurality of screws or bolts 10 whereby the member 2 may be rigidly and detachably secured to a suitable base 11 with the top wall 3 in elevated spaced relation with respect thereto.

As seen in Figs. 1, 2 and 3, the top wall 3 is slotted at 12 to receive therethrough a grinding wheel 13 mounted on the drive shaft 14 of an electric motor 15. The motor 15 is provided with a substantially circular split casing 17 having a pair of opposed substantially parallel flanges 18. The casing 17 is tightly clamped around the motor 15 by means of the bolt 19 and wing nut 20 which engage the exterior sides of the flanges 18.

The casing 17 is also provided with a pair of opposed (diametrically) bolts 21 which extend radially from opposite sides of the casing for reception within the arcuately shaped, oppositely disposed, spaced and substantially parallel slots 22 formed in the opposed, spaced and parallel bracket members 23. Wing nuts 24 co-operate with bolts 21 to lock the casing 17 and the motor 15 in adjusted position relative to the bracket members 23.

5 The bracket members 23 have integrally formed laterally extending flanges 25 at the lower ends thereof which are apertured to receive the screws or bolts 26 therethrough for detachable securement to the upper wall 3. As seen in the drawings, the brackets 23 support a hanger 27 at their respective forward and upper corners, the hanger 27 being apertured to receive therethrough the shank of an eyebolt 28. The slotted portion 29 of the eyebolt 28 is disposed between the flanges 18 and is adapted to receive a cross-pin 30 supported thereby. Lock and wing nuts 31 and 32, respectively, are mounted on the threaded shank of the eyebolt 28 and lock against opposed sides of the hanger 27 in adjusted positions.

10 The motor 15 is energized through the cable 33 which is connected with a suitable source of E. M. F.

The file holder is designated, in general, by the reference numeral 34, and comprises an elongated channel member 35 having a substantially inverted U-shaped transverse cross-section including a top wall 36, a pair of opposed spaced and parallel side walls 37 depending therefrom and terminating at their respective lower ends in outwardly turned oppositely disposed flanges 38. Each of the flanges 38 has a plurality of transverse apertures formed therein to receive bolts 39 which serve to secure an elongated bed plate 40 to the channel member 35, the bed plate 40 extending across the open lower end of the channel member 35 substantially throughout its length.

15 A plurality of laterally spaced elongated leaf springs 41 have one of their respective ends rigidly secured to the bed plate 40 while the other ends thereof engage against an elongated bottom spacer plate 42 which extends longitudinally of and parallel to the bed plate 40. As seen in Fig. 2, the opposed ends of the spacer plate 42 are bent downwardly at 43 and inwardly toward each other at 44 to surround the opposite ends of the bed plate 40 and constitute means for limiting the movement of the spacer plate 42 towards the top wall 36.

20 The top wall 36 is punched outwardly to form a dome 44 provided with a central aperture aligned with an aperture formed in the top wall 3 of the support member 2. The support member 2 and the file holder 34 are pivotally connected together by a bolt 45 which passes through the aligned apertures and is secured in position by the nut 46.

25 An elongated pawl 47 extends longitudinally of the top wall 36 and has one of its ends fixedly secured thereto by the screw 48, while the other end thereof projects through an opening 49 formed in the dome 44 and terminates at substantially the axis of rotation of the holder 34. As seen in Figs. 2, 5 and 7, the top wall 36 of the file holder 34 is slotted at 50 for registry with the slot 12 formed in the top wall 3 of the support member 2.

30 A second pawl 51 has one of its ends fixedly secured to the top wall 36, adjacent its rear end, by the screw 52, while the other end of the pawl extends downwardly through a slot 53 formed in the top wall 36.

35 As seen in Figs. 4 and 5, a plurality of leaf springs 54 have one of their respective ends fixedly secured to a side 37 of the file holder 34 while the other ends thereof bear against a second spacer plate 55 which extends longitudinally of the file holder. This spacer plate is at right angles to and bears against the spacer plate 42 and file 62. Vertical displacement of the spacer plate 55 is prevented by the top wall 36 and the bed plate 40 on which it is supported for lateral movement.

40 Longitudinal displacement of the spacer plate 55 is prevented by providing oppositely disposed lateral extensions 56 which are reversely bent at 57 to loosely surround the ends of the side wall 37.

45 A guide and spacer block 58 is secured on the top wall 36 adjacent the rear end thereof and is provided

with a groove 59 to slidably receive the rear marginal end of the top wall 3. A keeper plate 60 is supported on the block 58 with a side thereof in overlapping relation with respect to the rear marginal edge of the top wall 3. Block 58 and the keeper plate 60 are rigidly secured to the top wall 36 of the file holder 34 by means of a bolt 61.

In operation, a file 62 is inserted lengthwise between the top wall 36 and the spacer plate 42, making engagement with first pawl 51 until first tooth is positioned under grinding wheel 13 and then pawl 47. The abrading wheel 13 is brought into adjusted contact with the file teeth through the openings 12 and 50 by adjustment of the motor 15. This is accomplished by varying the position of the bolts 21 relative to the slots 22 and by changing the relative positions of the cross-pin 30 and the hanger 27 through the bolt 28 and the nuts 31 and 32. The motor 15 is then energized through the cable 33, and the operator then swings the file in arcs indicated by the arrows in Fig. 1.

As each tooth is sharpened, the operator advances the file one tooth forward and repeats the swinging operation of the file after first pulling backwardly thereon to make certain that the pawls have locked with the file teeth.

As the sharpening progresses the front end of the file becomes substantially enclosed by the file holder, and at that time the operator will utilize the file holder 34 and the guide and spacer block 58 or the rear end of the file as a handle to effect the arcuate movement.

It is deemed obvious that from the construction recited above, the spacer plates 42 and 55 enable the holder 34 to accommodate files of appreciable widths and thicknesses and will maintain the same in sharpening position under the influence of the leaf springs 41 and 54.

The invention described above, while having general application, is especially valuable to mechanics engaged in automobile body and fender repairs. To such mechanics, a sharp file having seven to eight teeth per inch is a most important tool. To sharpen such files it is important and critical that the pawl 47 have its file engaging end at the pivot point or axis of the holder, or at one inch or added equal increments of one inch therefrom. Additionally, in grinding files having seven or eight teeth per inch, the grinding wheel must be adjusted to engage that file tooth which is two inches (2") from the tooth falling directly under the axis of rotation of the holder. For example the arcuate curvature of files having seven or eight teeth per inch will be found to be struck from a radius of two inches. Thus, in the described embodiment, either file could be sharpened by positioning the grinding wheel for engagement with the fourteenth or sixteenth teeth thereof, or by measurement the grinding wheel could be spaced from the axis of rotation at two inches.

The hanger 27 is fixed in any suitable manner to the bracket members 23.

Having described and illustrated this invention in detail, it is to be understood that the embodiment herein disclosed is offered merely by way of example, and that the invention is to be limited only by the scope of the following claims.

I claim:

1. A file sharpening device comprising a support member having a pair of spaced sides disposed at an angle to each other and a wall secured to and bridging said sides, an elongated channel shaped member comprising a file holder, said member having an end thereof pivotally connected to said wall on one side thereof, said wall and said channel member each having openings formed

5 therein in register with each other, a pair of brackets mounted on the other side of said wall and projecting therefrom, and a motor driven grinding wheel adjustably supported on said brackets, said grinding wheel being adapted for insertion through said openings for engagement with a tooth of a file disposed within said holder.

2. A file sharpening device comprising a support member having a pair of spaced sides disposed at an angle to each other and a wall secured to and bridging said sides, 10 said wall having an opening formed therein, a pair of spaced substantially parallel brackets secured to one side of said wall and extending laterally therefrom, each of said brackets having an arcuate slot formed therein, a substantially cylindrical casing disposed between said brackets, said casing having means connected therewith for insertion within said slots for adjustment of said casing relative to said slots, an electric motor embraced and supported by said casing, a grinding wheel operatively connected with said motor, an elongated channel member having an end thereof pivotally secured to said wall 15 on the other side thereof and having an opening therein in registry with said opening formed in said wall, the other end of said channel member being free to oscillate between said side walls, and said grinding wheel being adapted for insertion through said openings for engagement with a tooth of a file disposed within said channel member.

3. A file sharpening device as defined in claim 2, and 20 said channel member having resilient means associated therewith to accommodate files having varying widths and thicknesses.

4. A file sharpening device comprising a support member having a pair of spaced sides disposed at an angle to each other and a wall secured to and bridging said sides, 25 said wall having an opening formed therein, a pair of spaced substantially parallel brackets secured to one side of said wall and extending laterally therefrom, each of said brackets having an arcuate slot formed therein, a casing for an electric motor adjustably supporting one end of an electric motor within said slots, 30 adjustable means associated with said casing for securing said casing in adjusted relation relative to said slots, a grinding wheel connected with said motor, an elongated channel shaped member having an end thereof pivotally connected with said wall and having an opening formed therein for registry with said opening formed in said wall, a spacer plate mounted within said channel member substantially parallel to said wall, resilient means mounted within said channel member constantly urging said plate towards said wall, a second spacer plate 35 mounted within said channel member, resilient means for urging constantly said last named plate at right angles toward the movement of said first plate under the influence of said first resilient means, and said channel member having an opening formed therein in registry with said first named opening to receive said grinding wheel therethrough.
